Fig. 2.

This cross-sectional diagram illustrates a mechanical assembly, possibly a pump or valve, featuring a central vertical structure and various components labeled with numbers 1 through 18. Key labeled parts include:

- 1: Bottom-most base or housing.
- 2: A ribbed circular component.
- 3: A curved component on the right side.
- 4: A curved component on the left side.
- 5: A ribbed circular component.
- 6: A ribbed circular component.
- 7: A ribbed circular component.
- 8: A ribbed circular component.
- 9: A ribbed circular component.
- 10: A ribbed circular component.
- 11: A ribbed circular component.
- 12: A ribbed circular component.
- 13: A ribbed circular component.
- 14: A ribbed circular component.
- 15: A ribbed circular component.
- 16: A ribbed circular component.
- 17: A ribbed circular component.
- 18: A ribbed circular component.

UNITED STATES PATENT OFFICE.

JASPER F. CULLIN, OF CLINTON, MICHIGAN.

INTERNAL-COMBUSTION MOTOR.

1,077,811.

Specification of Letters Patent.

Patented Nov. 4, 1913.

Application filed June 21, 1912. Serial No. 705,066.

To all whom it may concern:

Be it known that I, JASPER F. CULLIN, a citizen of the United States, residing at Clinton, in the county of Lenawee and State 5 of Michigan, have invented new and useful Improvements in Internal-Combustion Motors, of which the following is a specification.

This invention relates to internal combustion motors, the object in view being to provide a practical, reliable and efficient two-cycle motor, in which an auxiliary piston is used for scavenging and charging the cylinder, said auxiliary piston being arranged 10 and operating in such manner as to effect a thorough exhaust of the burnt gases from the exhaust port, and at the same time suck in a full and complete charge of fresh gas, preparatory to the next explosion.

20 By means of the construction, hereinafter described, all puppet valves at the usual places are entirely dispensed with, and the charging and exhausting of the cylinder is controlled entirely by the movement of the 25 piston, by means of which the ports are covered and uncovered at the proper times. Furthermore, all of the mechanism by which the intake and exhaust gases are controlled is included entirely within the body and 30 cylinder of the engine, thus making the engine effectively silent in operation.

With the above and other objects in view, the invention consists in the construction, combination and arrangement of parts, as 35 will be hereinafter more fully described, illustrated in the accompanying drawings, and pointed out in the claims hereunto appended.

In the drawings: Figure 1 is a vertical 40 section through an internal combustion motor, embodying the present invention, showing the position assumed by the parts at the moment of ignition. Fig. 2 is a similar view, showing the position of the pistons 45 just before the opening of the intake and exhaust ports. Fig. 3 is a similar view, showing the position occupied by the pistons when the inlet and exhaust ports are fully open. Fig. 4 is a similar view, showing the 50 position of the main piston just after the intake and exhaust ports are closed, and also illustrating the simultaneous position of the auxiliary piston, after it has fully exhausted the burnt gases from the cylinder. Fig. 5 55 is a section taken at right angles to the other

views, and illustrating the parts in the same position shown in Fig. 4. Fig. 6 is a cross section through the cylinder and auxiliary piston on the line 6—6 of Fig. 5. Fig. 7 is a horizontal section through the crank case 60 on the line 7—7 of Fig. 5, looking downwardly.

Referring now to the drawings, 1 designates the crank case of the motor, in which is mounted the crank shaft 2, carrying the 65 connecting rod 3 which is attached in the usual manner by a wrist pin 4 to the main piston 5.

The cylinder, represented at 6, is in the main of the ordinary construction, being 70 provided with the usual water jacket 7, and being further provided at suitable points with the inlet port 8 and exhaust port 9. The head 10 of the cylinder is provided with an inwardly projecting cylindrical extension 11 which sets well down into the cylinder, as shown in the drawings, and is provided adjacent to its lower edge with an expansion ring 12 to provide the necessary 75 compression. The cylinder head is further 80 provided with a spark plug hole 13, in which any suitable spark plug 14 may be screwed.

Mounted to reciprocate within the cylinder is the piston 5, the upper portion of which is extended in the form of a hollow 85 cylindrical sleeve or valve extension 15. This sleeve works up and down in the space between the cylindrical extension 11 of the head, and the inner wall of the cylinder itself, and is provided with an inlet port 16 90 and exhaust port 17, the said ports 16 and 17 like the ports 8 and 9 being of considerable lateral or horizontal extent, while comparatively narrow in height. The lower portion of the piston 5 is preferably solid, 95 as shown in the drawings, and is provided with one or more expansion rings 18 to provide the necessary compression.

Mounted to reciprocate within the extension 15 of the main piston is an auxiliary 100 piston 19 provided with an opening or passage 20 extending therethrough and terminating in a valve seat 21, against which operates an auxiliary piston check valve 22. The auxiliary piston 19 is carried by a tubular stem 23 which passes through an opening 24 in the main piston 5, and is attached, at its lower end, to a cross head 25. This cross head is mounted at its opposite ends to reciprocate on parallel guides 26 in the form 105 110

of rods, extending within the crank case and secured terminally to the top and bottom of said crank case. The cross head 25, as well as the stem 23 and auxiliary piston 19, are 5 normally pressed upward by means of coiled springs 27, encircling the guides 26 and interposed between the bottom of the crank case and said cross head 25:

The actuating means for the auxiliary 10 piston 19 consists of a cam 28 mounted fast on the crank shaft 2, and provided with a heart-shaped cam way 29, which works in conjunction with a roller 30 journaled on a stud 31 on the cross head 25. It will be understood that the cam 28 acts to move the 15 cross head 25 downward, whereas the springs 27 act to thrust the cross head upward, after the roller 30 is released by the cam 28.

The valve 22 is provided with a stem 32 20 which extends downward within the tubular stem or rod 23, and has connected to its lower end a valve seating spring 33 which acts to hold the valve normally closed, but yields to permit said valve to move open to 25 allow the fresh gas to pass from the space beneath the auxiliary valve into the space above the same.

In order to lubricate the walls in which 30 the sleeve 15 moves up and down, an oil pipe 34 leads from said space downward to the oil supply in the crank case, and said pipe is preferably provided at a suitable point with a check valve 35, and also with a regulating cock 36, by means of which the oil 35 may be allowed to pass to said space and prevented from being sucked backward. It will now be observed that the sleeve or extension 15, in working up and down in the space between the inner wall of the cylinder 40 and the extension 11, acts in the capacity of a pump, sucking oil through the lubricating pipe 34 in a sufficient quantity, regulated by the stop cock 36, to provide ample lubrication for the contacting surfaces at such 45 point. Furthermore, it will be seen that the walls so lubricated are above the explosion space of the cylinder, and therefore not subjected to the high degree of heat which is ordinarily found in the cylinder head.

50 In describing the operation of the engine, we will begin with the parts arranged, as shown in Fig. 1. With the pistons at this point, the ignition takes place, driving both pistons from the position shown in Fig. 1 55 inward to the point shown in Fig. 2, at which point the intake and exhaust ports begin to register. In moving slightly further inward to the extreme limit of movement, shown in Fig. 3, the inlet and exhaust 60 ports are fully opened. At this time, the auxiliary piston 19 starts to move outward, and in such outward movement, the burnt gases above the auxiliary piston 19 are forced outward through the exhaust ports 9 65 and 17. At the same time, a fresh charge

of gas is sucked inward through the ports 8 and 16, and the main piston 5 then begins to move upward, and upon reaching the position shown in Fig. 4, the inlet and exhaust ports are both closed, the auxiliary piston 70 having reached its outermost position and having thoroughly exhausted the burnt gases from the cylinder. The main piston then moves outward from the position shown in Fig. 4 to the position shown in Fig. 1, forcing the fresh gas ahead of it, through the auxiliary piston 19, past the valve 22, and into the combustion space in the head of the cylinder. As the main piston 80 moves outward, the cam 28 acts on the cross head 25 to draw the auxiliary piston inward again from the position shown in Fig. 4 to the position shown in Fig. 1. In this way, all of the fresh gas is forced past the valve 22 and compressed by the main 85 piston, in the combustion space above or beyond the auxiliary piston 19. This brings all of the parts back to the position shown in Fig. 1 ready for the following ignition and explosion.

90 As a result of the construction and operation hereinabove described, a perfect scavenging of the cylinder of all burnt gases is effected, in a two-cycle engine. A larger volume of fresh gas is drawn into the cylinder by reason of the auxiliary piston having a longer stroke than the main or power piston. The motor is silent in operation, due to the fact that there are no puppet valves arranged exteriorly of the motor, the 100 only valve of such nature being the one associated with the auxiliary piston, and this being located within the cylinder, and also within the cylinder extension of the main piston. Furthermore, by reason of the arrangement described, a practically gas-tight construction results. Furthermore, a quick opening and maximum dwell for both the intake and exhaust ports is accomplished, and the result is obtained without the use of 105 gears, chains, or other driving mechanism or elements outside of the crank shaft.

110 What is claimed is:

1. In a two-cycle internal combustion motor, a cylinder, a cylinder head having a 115 cylindrical extension projecting down into the cylinder, a piston having an outwardly projecting valve sleeve embracing said cylindrical extension, the cylinder and valve sleeve being provided with registering inlet and exhaust ports, and an auxiliary scavenging and charging piston working in the main piston.

2. In a two-cycle internal combustion motor, a cylinder, a cylinder head having a 125 cylindrical extension projecting down into the cylinder, a piston having an outwardly projecting valve sleeve embracing said cylindrical extension, the cylinder and valve sleeve being provided with registering inlet 130

and exhaust ports, an auxiliary piston working in the main piston, and a check valve carried by said auxiliary piston.

3. In a two-cycle internal combustion motor, a cylinder, a cylinder head having a cylindrical extension projecting down into the cylinder, a piston having an outwardly projecting valve sleeve embracing said cylindrical extension, the cylinder and valve sleeve being provided with registering inlet and exhaust ports, an auxiliary piston working in the main piston and actuated independently thereof, and a check valve in the auxiliary piston.

15 4. In a two-cycle internal combustion motor, a cylinder, a cylinder head having a cylindrical extension projecting down into the cylinder, a piston having an outwardly projecting valve sleeve embracing said cylindrical extension, the cylinder and valve sleeve being provided with registering inlet and exhaust ports, an auxiliary piston working in the main piston, and an outwardly opening check valve in the auxiliary piston.

25 5. In a two-cycle internal combustion motor, a cylinder, a cylinder head having a cylindrical extension projecting down into the cylinder, a piston having an outwardly projecting valve sleeve embracing said cylindrical extension, the cylinder and valve sleeve being provided with registering inlet and exhaust ports, an auxiliary piston working in the main piston, and an outwardly opening spring seated check valve in the auxiliary piston.

35 6. In a two-cycle internal combustion motor, a cylinder, a cylinder head having a cylindrical extension projecting down into the cylinder, a piston having an outwardly projecting valve sleeve embracing said cylindrical extension, the cylinder and valve sleeve being provided with registering inlet and exhaust ports, an auxiliary piston working in the main piston, a check valve therein, and a cam on the crank shaft for actuating the auxiliary piston.

45 7. In a two-cycle internal combustion motor, a cylinder, a cylinder head having a cylindrical extension projecting down into the cylinder, a piston having an outwardly projecting valve sleeve embracing said cylindrical extension, the cylinder and valve

sleeve being provided with registering inlet and exhaust ports, an auxiliary piston working in the main piston, a check valve therein, and cam and spring mechanism controlled by the crank shaft for actuating the auxiliary piston. 55

8. In a two-cycle internal combustion motor, a cylinder, a cylinder head having a cylindrical extension projecting down into the cylinder, a piston having an outwardly projecting valve sleeve embracing said cylindrical extension, the cylinder and valve sleeve being provided with registering inlet and exhaust ports, an auxiliary piston working in the main piston, a stem for the auxiliary piston passing through the main piston, and means on the crank shaft for actuating said stem. 60 65 70

9. In a two-cycle internal combustion motor, a cylinder, a cylinder head having a cylindrical extension projecting down into the cylinder, a piston having an outwardly projecting valve sleeve embracing said cylindrical extension, the cylinder and valve sleeve being provided with registering inlet and exhaust ports, an auxiliary piston working in the main piston, a stem therefor passing through the main piston, a cross 75 head connected to said stem, guides in the crank case on which the cross head slides, and a cam on the crank shaft for actuating said cross head.

10. In a two-cycle internal combustion 85 motor, a cylinder, a cylinder head having a cylindrical extension projecting down into the cylinder, a piston having an outwardly projecting valve sleeve embracing said cylindrical extension, the cylinder and valve 90 sleeve being provided with registering inlet and exhaust ports, an auxiliary piston working in the main piston, a stem therefor passing through the main piston, a spring pressed cross head connected to said stem, 95 guides in the crank case on which the cross head slides, and a cam on the crank shaft for actuating said cross head.

In testimony whereof I affix my signature in presence of two witnesses.

JASPER F. CULLIN.
